C. E. PRINCE

ELECTRIC CLOCK

Filed Aug. 6, 1924

*Inventor
Charles Edmond Prince*

By James L. (Mo) Attorney

UNITED STATES PATENT OFFICE.

CHARLES EDMOND PRINCE, OF BURCHETTS GREEN, ENGLAND.

ELECTRIC CLOCK.

Application filed August 6, 1924, Serial No. 730,449, and in Great Britain August 10, 1923.

In the specification filed with my United States Patent No. 1,493,279 I have described an electrically driven clock wherein, by the mechanical separation of the time-keeping element from the time-indicating mechanism, the oscillations of the former are substantially free. In the apparatus therein described periodic sustaining impulses are imparted to the time-keeping element by means of currents in an electric circuit established by the time-keeping element.

The present invention consists in certain improvements in or modifications of the invention claimed in the aforesaid specification. According to this invention, instead of deriving the periodic sustaining impulses from electric currents in a circuit established by the time-keeping element, the swing of the latter is sustained mechanically by energy stored in a spring or springs or a weight through the agency of a movable element of the electromagnetic circuit-breaker, which latter controls the operation of the time-indicating mechanism, and said movable element, consequent on the movement of the time-keeping element from one operative position to another, engages a spring or weight and energizes it to impart a sustaining impulse to the time-keeping element, or the movable element of the circuit-breaker may be provided with a light spring or the like which is brought into contact with the time-keeping element and imparts to it the required sustaining impulse.

The invention is illustrated in the accompanying drawings, wherein Fig. 1 is a diagrammatic representation of the circuit arrangement of an electric clock operating as described in the afore-mentioned patent specification; Figs. 2 and 3 are respectively a plan view and a sectional plan showing on an enlarged scale one construction of spring contact used in the control circuit of the clock; Figs. 4-8 inclusive are diagrammatic views in elevation; and Figs. 4^a-8^a inclusive are corresponding views in plan showing the relation of the pendulum and the spring contacts of the control circuit for various phases of the swing of the pendulum.

Referring to Fig. 1 the pendulum or timing element 1, which is pivoted at 2, carries a pair of contacts 27, 28, one on either side, which cooperate with contact springs 27', 28' connected respectively by leads 5 and 6 with coils 7, 8 of an electromagnetic circuit

reverser and with the fixed contacts 9, 10 thereof. A light spring contact arm 11 carried by a polarized armature 12 is moved into flexed engagement with contact 9 or 10, according as the coil 8 or the coil 7 is energized. The spring contact 11 is connected with one terminal of a battery 13, the other terminal of which is connected through lead 14 with a time-indicating device 15 and thence, through lead 16, with the pendulum suspension which in turn is electrically connected with the contacts 27 and 28.

Assuming the contact arm 11 of the circuit reverser to be in the position shown in flexed engagement with contact 9 and the pendulum 1 to be swinging from left to right, when contacts 27 and 27' engage a circuit will be established from battery 13 through spring contact 11, contact 9, energizing coil 7, lead 5, contacts 27', 27, lead 16, time-indicating device 15 and lead 14 back to battery. Consequent upon the current in coil 7 the armature 12 will be attracted towards the core of this coil and away from the core of coil 8, and the spring contact arm 11 will consequently break the circuit at contact 9 after a time lapse determined by the inertia of the armature and the degree of flexure of spring 11, and be thrown over against contact 10 to establish another circuit from battery 13, through contact arm 11, contact 10, coil 8, lead 6, contacts 28', 28 (when, upon the return swing of the pendulum, these are brought into engagement), lead 16, time-indicating device 15 and lead 14 back to battery.

It will be seen that the establishment of the control circuit by the pendulum, either through contacts 27, 27', or 28, 28', shifts the circuit breaker or reverser from one operative position to the other and the current which effects this also traverses the energizing coil of the time-indicating mechanism, which may be of any suitable step-by-step electrically operated kind. Also, since upon each swing of the pendulum the contacts 27, 27' (or 28, 28') are in engagement during quite a large proportion of each swing, it follows that they will still be in contact at the moment that the circuit breaker or reverser is thrown over from one operative position to the other, and consequently the actual breaking of the circuit to interrupt the current flow takes place, not at the pendulum or control contact, but always at the circuit reverser contact.

While in some respects it is immaterial whether the pendulum contacts 27, 28 are rigid and the fixed contacts 27', 28' yielding or conversely, the former arrangement is preferred as it affords convenient means for applying mechanically to the pendulum a periodic sustaining impulse of constant value. A convenient form of yielding contact for the purposes contemplated is shown 10 in Figs. 2 and 3, wherein 24 is a metal tube having one or more longitudinal slits at its inner end which fits friction tight over a boss 25 on a crank arm 26 fulcrumed on a terminal block suitably connected in the 15 control circuit. Inside the tube 24 is a spring contact wire 27' preferably having a contact surface of a nonoxidizing character, the outer or free end of which is exposed by a portion of the tube 24 being cut away 20 as indicated at 24', while the inner fixed end is rigidly secured to the tube 24. The distance of the spring contact 27' from the central position of the pendulum can be adjusted by turning the crank arm 26 about 25 its fulcrum, any suitable means being provided to secure the contacts in the positions to which they have been adjusted.

The contacts 27, 28 on the pendulum may consist of rigid platinum wires arranged 30 substantially at right angles to the spring contact wires 27', 28' (Figs. 4-8^a). As the pendulum swings outwardly on either side from the central position the contact elements on that side engage and establish the 35 circuit of coil 7 or coil 8 as the case may be. The spring 27' or 28' is flexed by the pendulum during the remainder of the outward swing and reacts on the pendulum during the corresponding part of the inward swing, the energy stored in the spring by 40 its flexure being thus returned to the pendulum. By applying tension by external means to the spring 27', for example, so that it acts on the pendulum over a longer distance during the inward swing than that 45 over which the pendulum acts upon the spring to energize it during the outward swing, more energy is imparted to the pendulum upon the inward swing than is absorbed from the pendulum upon the outward swing, and it is thus possible by means 50 of this residuum of energy to compensate the resisting forces opposing the movement of the pendulum and thereby maintain the 55 amplitude of its swing. With this object the spring contact 27' is displaced so as to be partly tensioned or energized, after the pendulum on its inward swing has moved away from it, by means of a movable member, for example a pin 29 (Figs. 1, 4-8^a), attached to the armature of an electromagnetic device included in a circuit established 60 by the operation of the contacts 27, 27' or 28, 28'. This electromagnetic device may 65 conveniently be the same device as that

which operates to break the energizing circuit, viz, the circuit-breaker 7, 8 (Fig. 1). The changes in position of the cooperating parts are illustrated in Figs. 4-8^a. In Figs. 4 and 4^a the pendulum 1 is shown in the intermediate position moving from right to left and the pin 29 in its inoperative position in so far as regards the flexure of spring contact 27'. In Figs. 5 and 5^a the pendulum has moved over to establish contact 75 between the contact elements 28 and 28', thereby energizing electromagnet 8 and shifting the armature 12 from one operative position to the other. This movement of the armature, with which pin 29 is rigidly connected, brings the latter into engagement with the spring contact 27', displacing the latter outwardly to a definite extent which can be adjusted by appropriate means.

The pendulum on its return swing towards the right first establishes contact with the spring 27' in its displaced position, as shown in Figs. 6 and 6^a, thereby again energizing electromagnet 7 and consequently shifting the armature 12 back into its other operative position, so that the pin 29 is withdrawn into its inoperative position, as shown in Figs. 7 and 7^a. The pendulum continues its outward movement to the right, still further flexing the spring 27', until it reaches its limiting position as shown in Figs. 7 and 7^a, in which position the displacement of the spring 27' is a maximum. On the return inward swing of the pendulum the spring follows up the pendulum over the complete range of its flexure, since the pin 29 has been retracted and is no longer in a position in which it can arrest the return of the spring 27' to its initial position, as shown in Figs. 8 and 8^a and 7 and 7^a. It will be seen therefore that during the return or inward swing of the pendulum the tension spring 27' acts through an additional range upon the pendulum as compared with the range of engagement on the outward swing, namely over the distance indicated by the difference in the position of the spring 27' as shown in Figs. 5, 5^a and 6, 6^a, and its position as shown in Figs. 4 and 4^a.

By such a method of sustaining the oscillations of the time-keeping element the amplitude and time-keeping are entirely independent of variations, from whatever cause, in the electric energizing circuit. Further, the amplitude of swing can be readily adjusted by altering one or both of the limiting positions of the spring acting upon the time-keeping element.

Having thus described the nature of the said invention and the best means I know of carrying the same into practical effect, I claim:

1. An electrically driven clock, comprising a time-indicating mechanism, an oscillating time-keeping element mechanically 130

- separate from the time-indicating mechanism, an electromagnetic device included in a circuit controlled by the time-keeping element, a spring external to the oscillating time-keeping element and arranged to be deflected and energized by the latter towards the end of an oscillation, and an element actuated by the said electromagnetic device and operating to deflect and energize said 10 spring prior to its engagement by the oscillating time-keeping element, said electromagnetically actuated element being withdrawn from engagement with said spring during the period of engagement therewith 15 of the oscillating time-keeping element.
2. An electrically driven clock, comprising a time-indicating mechanism, an oscillating time-keeping element mechanically separate from the time-indicating mechanism, an electromagnetic circuit breaker included in a circuit controlled by the time-keeping element and itself controlling the operation of the time-indicating mechanism, a fixed spring contact external to the oscillating time-keeping element and arranged to 20 be engaged by the latter towards the end of a swing thereof, and a movable element on the electromagnetic circuit breaker operating to deflect and energize the said spring contact prior to its engagement by the oscillating time-keeping element. 25
3. An electrically driven clock, comprising a time-indicating mechanism, an oscillating time-keeping element mechanically separate from the time-indicating mechanism, a control circuit arranged to be closed by the operation of the oscillating time-keeping element, an auxiliary circuit interrupter operating to open the said control circuit, a spring arranged to act on the time-keeping element during part of its oscillation, electromagnetic means for intermittently tensioning said spring comprising two coils alternately brought into the energizing circuit and a single battery supplying current alternately to said coils. 30 35 40 45

In testimony whereof I have signed my name to this specification.

CHARLES EDMOND PRINCE.
